M. EISNER & J. MENDELSON.

STAND.

No. 16,359.

Patented Nov. 3, 1885.

UNITED STATES PATENT OFFICE.

MORITZ EISNER AND JOSEPH MENDELSON, OF PHILADELPHIA, PA.

DESIGN FOR A STAND.

SPECIFICATION forming part of Design No. 16,359, dated November 3, 1885.

Application filed August 27, 1885. Serial No. 175,513. Term of patent 3½ years.

To all whom it may concern:

Be it known that we, MORITZ EISNER and JOSEPH MENDELSON, both citizens of the United States, residing in the city and county of Philadelphia, State of Pennsylvania, have invented and produced a new and original Design for a Stand, of which the following is a specification, reference being had to the accompanying photographic illustration, forming part thereof.

The leading features of our design for a stand are rows of rings, crossed pieces, side pieces, cross-bars, and top ornaments.

A represents a wire stand, consisting of side pieces, *a*, cross-pieces *b*, a prop, *c*, crossed bars *d*, and horizontally-extending rows of rings *e*. From the center of the top of the stand rises an ornament, *f*, of rings, and from each side rise forks *g*, with a ring, *h*, on each limb thereof. The feet *j* are curved and twisted.

We claim—

1. A design for a wire stand, consisting of the side pieces, *a*, cross-pieces *b*, prop *c*, crossed bars *d*, rings *e*, and center top ornament, *f*, substantially as described.

2. A design for a wire stand, having the side pieces, *a*, rings *e*, crossed bars *d*, prop *c*, forks *g*, rings *h*, and twisted feet *j*, substantially as shown.

3. A design for a wire stand, consisting of the side pieces, *a*, cross pieces *b*, cross-bars *d*, rings *e*, center ornament, *f*, and side forks, *g*, as shown and described.

MORITZ EISNER.
JOSEPH MENDELSON.
